UNITED STATES PATENT OFFICE.

JORAM A. ZIEGLER, OF CHATTANOOGA, TENNESSEE, ASSIGNOR TO ELLIOTT-FISHER COMPANY, OF NEW YORK, N. Y., A CORPORATION OF DELAWARE.

RIBBON MECHANISM FOR TYPE-WRITING MACHINES.

1,115,648.

Specification of Letters Patent.

Patented Nov. 3, 1914.

Application filed February 6, 1911. Serial No. 606,913.

To all whom it may concern:

Be it known that I, JORAM A. ZIEGLER, a citizen of the United States of America, residing at Chattanooga, Tennessee, in the county of Hamilton and State of Tennessee, have invented certain new and useful Improvements in Ribbon Mechanism for Type-writing Machines, of which the following is a specification.

10 This invention relates to typewriting machines, and more particularly to ribbon mechanism adapted for use in connection with a work element in the form of a manifold strip or web.

15 The invention is of the same general character as that of my pending application No. 549,920 and its general object is likewise to arrange the ribbons for accommodation in opposite folds of a long manifold

20 sheet or strip without interfering with the feed of the strip in a longitudinal direction.

A distinguishing object of the present arrangement is to provide a more compact mounting of the ribbon mechanism by so 25 modifying the structure that the ribbon spools may be located between the main bearings of the platen spindle and closely adjacent to the ends of the platen.

Another object is to simplify the construction and arrangement of the ribbon guides and to dispose the same in more accessible position to facilitate their manipulation by the operator.

Another object is to arrange certain of 35 the ribbon guides for removal from their normal positions in order to facilitate the arrangement of the ribbon mechanism for use in connection with separated strips or webs of paper when the use of a manifold 40 strip is not desired.

Other objects of the invention will more fully appear hereinafter.

In the accompanying drawings—Figure 1 is a front elevation of a portion of a typewriter equipped in accordance with my invention. Fig. 2 is a detail perspective view of the main supporting frame of the ribbon mechanism. Fig. 3 is a front elevation of a portion of the structure shown in Fig. 1. Fig. 4 is a vertical section on the line 4—4 of Fig. 1. Fig. 5 is a detail perspective view of one of the ribbon guides, and Fig. 6 is a sectional view showing the relative

arrangement of the manifold paper strip and ribbons.

Each part, wherever shown, is indicated by its appropriate reference character.

1 indicates the usual platen carried by the spindle 2 equipped with knurled wheels 3 and mounted in bearings 4 in the end frames 5 of the platen carriage 6. Adjacent to the right hand bearing 4 the spindle is provided with a line space ratchet 7 coating with other elements (not shown) of the usual line space mechanism to effect the step-by-step rotation of the platen and the consequent line space feed of the work element. Loosely mounted on the platen spindle 2 are four ribbon spools 8, 9, 10 and 11 arranged in pairs immediately adjacent to opposite ends of the platen.

Attached to the ribbon spools are gears 8^a, 9^a, 10^a and 11^a adapted to be engaged by gears 8^b, 9^b, 10^b and 11^b mounted on sleeves 12 and 13 fixed to a shaft 14 mounted in bearings 15 extended rearwardly from the main ribbon supporting frame 16 having apertured depending ends 17 located just beyond the end frames 5 and pierced by the platen spindle. Secured to the outer ends 18 of the shaft 14 are gears 19 each of which is geared to the carriage spindle through the medium of a pinion 19, a gear 20 provided with pawls 21 and a ratchet 22 secured to the spindle 2 and coating with the pawls 21 to establish a driving connection between the spindle 2 and the shaft 14 when said spindle is rotated in one direction. Also mounted on the spindle 2 between each pair of spools is a gear 23 connected by pawl and ratchet mechanism not shown, with the spindle 2 and constantly meshing with one of two gears 24 fixed to the sleeves 12 and 13. The pawl and ratchet mechanism of the gears 23 is disposed oppositely 95 to the pawl and ratchet mechanism connecting the spindle 2 with the gears 20. Therefore, when the spindle is rotated in one direction, the shaft 14 will be driven through the medium of the gears 18 and 100 when the spindle is rotated in the opposite direction, the shaft 14 will be rotated through the medium of the gears 23 and 24. It will be observed, however, that the direction of rotation of the shaft 14 is uniform.

The gears 8^b and 9^b and similarly the gears 10^b and 11^b are separated by a somewhat greater interval than the adjacent spool gears so that both spool gears can never be in mesh at the same time with the gears on the shaft 14. On the contrary, the spacing of the gears is such that by the endwise shifting of the shaft 14 either spool of a given pair of spools can be brought in mesh with the shaft and the direction of the ribbon feed thereby reversed, since it will be understood that in this type of ribbon motion a ribbon has its opposite ends wound upon the two spools located at one end of the platen and may be fed in one direction or the other, accordingly as one or the other of the spools is positively driven.

The ribbon reversing mechanism includes, in addition to certain of the described elements, a reversing lever 25 mounted on one of two rectangular frames 26 which surround the frame 16. Within the frames 26 are disposed yokes 27 which engage the opposite ends of the sleeves 12 and 13. One of these yokes is provided with a pin 27' which extends through a cam shaped slot in the reversing lever 25 so that when said lever is shifted the adjacent yoke will be moved to shift the shaft 14 sufficiently to reverse the feed of the ribbons.

The described mechanism for effecting the ribbon feed and reverse is substantially like that disclosed in my pending application and has therefore not been illustrated in detail and need not be further described.

As already intimated, each of the two ribbons *a* and *b* is led from one spool toward the opposite end of the platen and thence back again to another spool adjacent to the one from which the ribbon starts. That is to say, both ends of the ribbon are wound upon spools at the same end of the platen and an intermediate portion or loop of the ribbon is carried to a guide located at or adjacent to the opposite end of the platen. Each ribbon is thus doubled upon itself and overlaps a looped or doubled portion of the other ribbon, see Fig. 6. This arrangement enables each ribbon to extend into the open side of a folded paper strip and to extend to the closed side of the fold where it must necessarily terminate or else return through the same or open side of the strip. It follows that the ribbon guides *a'* and *b'* which are located within the folds of the paper strip must be supported outside of the fold and it is desirable that these guides be mounted at the front of the machine where they are readily accessible. For this reason I have devised ribbon guides both for the looped or folded portions of the ribbons and for those portions of the ribbons lying immediately adjacent to the spools and have arranged for the mounting of

these several guides on the main supporting frame 16 of the ribbon mechanism.

Carried by the frame 16 directly above the front portion of the platen is a paper guide 28 comprising front and rear members 29 and 30, the front member being in the form of a plate the upper edge of which constitutes a paper cutter. Pivotally connected to the outer ends of the guide member or plate 29 are two ribbon guide bars 31 and 32 which extend in opposite directions and are formed with terminal guide loops 33 and 34 portions of which define the ribbon guides *a'* and *b'*, since it will be seen that each of the ribbons *a* and *b* is passed through one of the ribbon guide loops and thence led back to its spool in the manner described.

For the purpose of limiting the movement of the guide bars 31 and 32 in one direction, said bars are provided with stop arms 35 located adjacent to their pivots and engaging fixed stops 36, see Fig. 3. Thus the weight of the bars and the strain imposed thereon by the ribbons retain the bars in proper normal position, but when desired, the bars 31 and 32 may be swung back away from the platen in the event that it is desired to arrange the ribbon mechanism for use in connection with separated or unfolded work elements. This may obviously be done by unwinding one end of each ribbon and rewinding the same on a spool at the opposite end of the platen so that each ribbon will extend from a spool at one end of the platen to a spool at the opposite end of the platen instead of being wound upon two spools both located at the same end of the platen.

To properly guide the ribbons into the proper plane as they leave or approach the spools a ribbon guide 37 depends in front of each spool from the main frame 16. The guides 37 are in the form of plates 38 having their upper ends secured to the frame 16 and carrying horizontal guide rollers 39 over which the ribbon is led from the angular guide 40 secured to a fixed portion of the plate 38. The guides 37 are similar to those disclosed in my pending application, except that in the present instance these guides as well as the guide bars 31 and 32 for the looped portions of the ribbons are all extended from the plate or frame 16 located above the platen.

It will be understood that when the ribbons are arranged as shown and described they will be retained within opposite folds of a manifold sheet or strip *x*, see Fig. 6, and that the ribbon supporting and guiding means interfere in no way with the feed of the manifold strip which may therefore be of indeterminate length or what is known as a continuous web. It may also be mentioned that in classes of work where the

feed of the ribbon is not material, the ribbon, instead of being looped or doubled, may merely be extended into the folds of the paper and its extremity fixed to one of the guides a' or b' .

It is thought that the foregoing description taken in connection with the accompanying drawings will be sufficient to constitute a complete disclosure of the invention and I reserve the right to effect such modifications of the illustrated structure as may come fairly within the scope of the protection prayed.

What I claim is:—

15 1. The combination with a platen carriage, platen and platen spindle, of two pairs of ribbon spools each pair interposed between one end of the platen carriage and the adjacent end of the platen, inking ribbons each carried by the spools of one of said pairs of spools and extended opposite the platen, and guiding means for said ribbons.

20 2. The combination with a platen, of ribbon supporting means, a longitudinally folded web or strip led over the platen, ribbons extended from said supporting means into the fold of said strip, and a ribbon carrier extended into said fold of the manifold strip to engage and support the ribbon, said carrier being supported exclusively outside of said fold and intermediate of the ends of the strip and movable into and out of operative position.

25 3. The combination with a platen, of ribbon supporting means mounted beyond the opposite ends thereof, a manifold web or strip led opposite the platen, ribbons extended from said supporting means into 30 opposite folds of said strip, and ribbon carriers extended into said opposite folds of the manifold strip to engage and support the ribbons, said carriers being supported

exclusively outside of said folds and intermediate of the ends of the strip and movable into and out of operative position.

4. The combination with a platen, of ribbon spools mounted beyond the opposite ends thereof, a manifold web or strip led opposite the platen, ribbons extended from 45 said spools into opposite folds of said strip, and ribbon carriers extended into said opposite folds of the manifold strip to engage and support the ribbons, said carriers being in the form of arms pivotally supported 50 outside of the folds of the strip.

5. The combination with a platen, a pair of ribbon spools located adjacent to each end thereof, a horizontal supporting plate, ribbon guides depending from said plate 55 and disposed opposite the spools, a paper guide carried by the plate, and other ribbon guides carried by the paper guide.

6. The combination with ribbon spools and a platen, of a pair of ribbon guide rods 60 disposed in crossing relation and each having a ribbon guide at one end and pivotally mounted at its opposite end, a support for said guide arms and separate ribbons guided by said rods.

7. The combination with a platen, of ribbon spools adjacent to the ends thereof and a unitary structure including a horizontal supporting plate, ribbon guides depending from the plate opposite the spools, a paper 75 guide carried by the plate, and additional ribbon guides extending from the paper guide to engage the ribbon at points between the ribbon guides first named.

In testimony whereof I affix my signature 80 in presence of two witnesses.

JORAM A. ZIEGLER.
